UNITED STATES PATENT OFFICE

100,829

DESIGN FOR AN INITIAL OR OTHER CHARACTER BEARING HOLDER

Joseph O. Pollack, Chicago, Ill.

Application May 20, 1936, Serial No. 62,736

Term of patent 14 years

To all whom it may concern:

Be it known that I, Joseph O. Pollack, a citizen of the United States, residing at Chicago, in the county of Cook and State of Illinois, have invented a new, original, and ornamental Design for an Initial or Other Character Bearing Holder, of which the following is a specification, reference being had to the accompanying drawing forming a part thereof.

Fig. 1 is a front elevational view of an initial or other character bearing holder showing my new design;

Fig. 2 is a rear elevational view thereof, the particular initials shown being merely illustrative; and

Fig. 3 is an edge view of the holder.

I claim:

The ornamental design for an initial or other character bearing holder as shown and described.

JOSEPH O. POLLACK.
